UNITED STATES PATENT OFFICE.

WILLIAM J. MURDOCK, OF CLINTON, INDIANA.

STOP FOR TALKING-MACHINES.

1,391,565.

Specification of Letters Patent. Patented Sept. 20, 1921.

Application filed May 29, 1920. Serial No. 385,229.

To all whom it may concern:

Be it known that I, WILLIAM J. MURDOCK, citizen of the United States of America, residing at Clinton, in the county of Vermilion and State of Indiana, have invented new and useful Improvements in Stops for Talking-Machines, of which the following is a specification.

This invention relates to improvements in phonographs and has for an object the provision of means for automatically stopping the operation of the machine at the end of a record.

Another object is the provision of a phonograph attachment in which the motor operated to automatically move a brake member into engagement with the turntable at the end of the record, so that the operation of the motor will be automatically stopped.

With the above and other objects in view, the invention further includes the following novel features and details of construction, to be hereinafter more fully described, illustrated in the accompanying drawings and pointed out in the claims hereto appended.

In the drawings:—

Figure 1 is a plan view illustrating the application of the invention with the parts in normal position.

Fig. 2 is an edge view of the same.

Fig. 3 is a view similar to Fig. 1, but showing the parts in a position opposite to that shown in the said Fig. 1.

Fig. 4 is a like view illustrating the position of the parts with the brake as applied, a fragmentary portion of the turntable flange being shown.

Referring to the drawings in detail, where in like characters of reference denote corresponding parts, the reference character 10 indicates the assembly plate of a spring motor of the type usually employed in phonographs, while 11 indicates the tone arm and 12 a form of governor commonly used in machines of this character.

The invention comprises an arm 13, which carries at one end a split band 14, for attachment to the tone arm 11 and having its free ends secured together as indicated at 15. The opposite end of the arm 13 is bifurcated and carries set screws 16, which operates in slots 17, provided in the bifurcated end of a link 18. This link has one end pivotally connected as shown at 19 to a disk 20, the latter being mounted for rotation upon a short shaft 21 extending from

the plate 10. The disk 20 is designed to be rotated by the movement of the tone arm 11 as the latter travels over the surface of a record during the operation of the machine, 60 the movement of the said disk being limited in one direction by means of a tooth 22, which engages the stop 23 carried by the plate 10.

The disk 20 is designed to be alternately 65 moved in opposite directions during the playing of the record and for the purpose of moving the disk in a direction opposite to that due to the movement of the tone arm 11, the said disk is provided with an additional 70 tooth 22^a which is designed to be engaged by an arm 24 carried by a star wheel or gear 25. This gear is rotatably mounted upon a short shaft 26, which is also carried by the plate 10 and movement of this gear is 75 effected through the medium of a finger or stud 27, which projects radially from the shaft 28 which carries the turn-table upon which the record is supported, the turn-table being shown by dotted lines as indicated at 80 29. Both the disk 20 and the gear 25 have connected thereto the ends of coil springs 30 and 31 respectively, while the opposite ends of these springs are secured to the shafts 21 and 26, in which the disk and gear 85 are mounted.

Pivotedly mounted upon the disk 20 as indicated at 32, is a lever 33, one end of which is positioned for engagement with the arm 24, while its opposite end is designed 90 to engage one end of a brake arm 35. This brake arm is pivotally mounted as shown at 36 upon a plate 37 and has connected thereto a spring 38. The end of the brake arm opposite that engaged by the lever 33 is positioned for engagement with a pivoted disk 39 having a notch 40 in its periphery. Mounted upon this disk is a friction member 41 which is urged into engagement with the flange of the turntable by means of a spring 100 42. In addition, the disk 39 is provided with an operating handle 43.

In the operation of the invention, after the machine has been started, the movement of the tone arm over the record will, through 105 the medium of the arm 13 and the link 18, rotate the disk in a direction toward the stop 23, until the latter is engaged by the tooth 22. In the meantime, the operation of the turn table shaft 28 will operate the 110 gear 25, whose arm 24 will engage the tooth 22^a and move the disk in an opposite direc-

- tion to prevent engagement of the arm 24 and the adjacent end of the lever 33. When the tone arm 11 stops at the end of the record, movement of the arm 13 will be arrested 5 and will therefore impart no rotary movement to the disk 20, whereupon the lever 33 will remain in position for engagement by the arm 24 and the latter will be moved upon its pivot to engage one end of the brake arm 35, so as to cause the opposite end of the last mentioned arm to be disengaged from the notch 40 and permit the friction member 41 to be moved into engagement with the turntable flange.
15. When it is again desired to start the operation of the phonograph, the disk 39 is rotated by means of the handle 43 until the end of the arm 35 engages the notch 40, whereupon the friction member will be disengaged and the turntable permitted to rotate.

The invention is susceptible of various changes in its form, proportions and minor details of construction and the right is herein reserved to make such changes as properly fall within the scope of the appended claims.

Having described the invention what is claimed is:

1. The combination with a phonograph, 30 of a brake, a rotatable element, a pivotally mounted spring pressed brake actuating lever carried by the rotatable element and

adapted for engagement with the brake, means operated by the movement of the tone arm over the record for moving the brake 35 actuating lever away from the brake and means operated by the motor when the tone arm movement ceases to engage the brake actuating lever and apply the brake.

2. The combination with a phonograph, 40 of a brake, a rotatable element, a brake actuating lever carried thereby, means operated by the movement of the tone arm over the record for moving the actuating lever away from the brake and an arm carried by the 45 turn table shaft and engageable with the brake actuating lever to apply the brake when the tone arm movement ceases.

3. The combination with a phonograph, 50 of a brake, a rotatable element, a brake actuating lever carried by the rotatable element, means whereby the operation of the turntable shaft will move the rotatable element in one direction and bring the brake actuating member into position for operating the 55 brake, means operated by the movement of the tone arm over the record for moving the rotatable element in an opposite direction and means whereby the operation of the turn table shaft will engage the brake actuating 60 lever and apply the brake when the movement of the tone arm ceases.

WILLIAM J. MURDOCK.
